REMOTE CONTROL SYSTEM FOR ELECTRIC CIRCUITS

Application filed February 15, 1927, Serial No. 168,381. Renewed April 2, 1930.

Our invention relates to an improved remote control system for electric circuits and has for an object to provide means operable from a remote station or a plurality of different stations, to control one or more electric circuits.

Another object of our invention is to provide means at the remote station to indicate whether the circuit controlling means 10 has properly functioned.

Another object of our invention is to provide a system whereby the power or current strength in a circuit may be varied from a distant point.

15 A specific object of our invention is to provide a switch of improved form and operable through a simple two-wire control circuit to either open or close a main circuit.

Another object is to provide a switch in 20 which the make and break of a main circuit is abrupt, thereby avoiding destructive sparking.

Another object is to provide a system including a remote control switch of the kind 25 above specified in which the switch will be operated by a small amount of power tapped from the main circuit.

Another object of the invention is to provide a remote control switch in which a 30 number of circuits may be simultaneously opened and closed, or in which the circuits may be successively opened or closed.

Another object is to provide a remote control switch of very simple and rugged construction which will be inexpensive to 35 manufacture.

Our improved system may be found useful in connection with the control of power stations from remote points, for the control of lamps in electric sign-boards, etc. A particular application for which our system is well suited, has to do with radio receiving apparatus. It is well known that the loud speaker of a radio receiving set should be located at a considerable distance from the set in order to insure good reception. It is convenient to have means for throwing the current, to the set, on or off from a point adjacent the loud speaker. It is also of advantage to provide for turning the set on or

off from various points about a room or even from another room, and our improved system of remote control provides a simple means of carrying out this desired control of the set. To be sure the power lines leading into the set could be tapped at various points in a room, but the objection to such a system lies in the fact that the power lines could not be installed within the requirements of insurance underwriters without considerable expense. By our system the switch may be placed at or adjacent a set, while the switch controlling circuit, carrying a very insignificant amount of electric current and well within the safety regulations of the underwriters, could be extended to any point desired.

While our system is admirably adapted for the control of radio-receiving apparatus, we do not wish to place too much emphasis on this particular application because our switch is equally as well adapted to a wide variety of other applications.

With the above noted objects in view and with others which will appear in the following specification, we shall now describe an embodiment of our invention and several alternative variations and shall then define the scope of our invention in the claims.

Referring to the drawings, 80 Figure 1 is a partly diagrammatic view showing a front elevation of our improved remote control switch and certain electrical apparatus and circuits connected therewith, the switch being shown open;

Fig. 2 is a view in front elevation of a portion of the switch on an enlarged scale showing the switch closed; and

Fig. 3 is a view in transverse section taken on the line 3—3 of Fig. 2.

Referring particularly to Figures 1 to 3 inclusive, we show at 10 a panel or base-board of insulation material on which our switch mechanism is mounted. Secured to the face of the panel is a U-shaped soft iron core 11, one leg of which carries a magnet coil 12. The panel may be recessed or cut away as indicated at 13, to clear the coil. Secured to the other end of the core is a strap 14 in which is pivoted an armature 101

arm 15. The arm 15 is normally held up by a tension spring 16 against a stop 17 projecting from the strap. When the coil 12 is energized the arm 15 will be drawn down to a position shown by broken lines in Fig. 2, forming a closed circuit.

Pivoted to the free end of the arm 15 is a pawl 18 formed with a hooked upper end which is adapted to engage the pins 19 of a lantern gear 20 (see Fig. 3). The lantern gear comprises an inner and an outer wheel held in mutually spaced relation by the pins 19, and the outer wheel 21 has the form of a ratchet or star wheel with flat peripheral edges terminating in teeth 22. There are twice as many pins 19 as teeth 22. The lantern gear is suitably mounted to turn on a stud 23 projecting from the panel. Bearing against the wheel 21 is a spring contact finger 24 secured at one end to a bracket 25 on the panel board, and carrying at the other end a yoke 26. When the finger 24 is raised, the yoke 26 bridges a pair of contact points 27 and 28 carried by the panel board. The contact points are connected to series terminals of a main circuit, and the yoke thus serves to open or close the main circuit. To insure proper seating upon the contact points the yoke is secured to the finger with a certain amount of play.

In operation, every time the magnet coil 12 is energized, the pawl 18 will be pulled downward, turning the wheel 21 through a small angle, this angle being half the angle embraced between two teeth 22, so that if at the end of one operation, the finger 24 is resting on the outer point of a tooth 22, as shown in Fig. 2, the next operation of the magnet will swing the wheel 21 to the position shown in Fig. 1, when the spring will drop upon one of the flat peripheral edges of the star wheel and the tooth 22, which immediately before had held up the finger 24, will now enter an opening 29 formed in the finger. The pawl 18 is pulled inward against the pins 19 by a light coil spring 30 extending from the pawl to the arm 15. Owing to the fact that the magnet operates very quickly, it is necessary to provide a stop to prevent the pawl from swinging out centrifugally, and pulling the wheel 21 through a greater angle than is desired. To this end we have provided a stop which is in the form on an eccentric collar 31 secured to the base-board by means of a screw 32. The collar may be turned to vary the throw of the pawl 18 and may then be held at the desired adjustment by tightening the screw 32. The hooked end of the pawl has a curved upper surface which will permit it to ride past the pins 19 on its upward stroke, so that every time the coil 12 is de-energized, the pawl 18 will rise and hook over the next adjacent tooth, and upon the next operation of the magnet, the wheel 21 will be turned

from the position shown in Fig. 1 to that shown in Fig. 2.

To energize the magnet 12, we may tap off a certain amount of current from the main circuit. If the current in the main circuit is alternating, this is accomplished very readily by using a transformer to operate the magnet. On the panel board there are three binding posts 34, 35 and 36. Opposite terminals of the magnet coil 12 are connected to the binding posts 34 and 36 respectively. One terminal of the secondary coil of the transformer 33 is connected to the binding post 34, and the other terminal to the binding post 35. Leading from the binding posts 35 and 36 respectively, are the two wires 37 and 38 of a control circuit. Bridged across this control circuit are switches or push buttons 39, located at convenient points, and whenever the button is pressed to close the circuit across the wires 37 and 38, the magnet 12 will be energized, drawing down the armature 15 and operating the contact finger 24 to open or close the main circuit. In order to adapt the magnet for use on alternating current, the free end of the leg of the core 11 which carries the coil 12 is bifurcated, and one of the bifurcations carries a shading coil 40. In Fig. 1, we have indicated the main circuit as including the power lines 41 and 42 with the former line running directly to one terminal of the work and the latter line running to the contact point 27, while a line 43 runs from the contact point 28 to the other terminal of the work. The work in this case, is indicated as a motor generator, the motor 44 of which is connected to lines 41 and 43. The generator 45 has one terminal thereof connected by line 46 to the binding post 36 or the wire 38, while the other terminal is connected to a line 47. Bridged across the lines 38 and 47 are variable resistances 48, these resistances being preferably placed adjacent the push buttons 39. The adjusting arm 49 of each variable resistance 48 is connected to one terminal of a motor 50 or other suitable electrical device, whose other terminal is connected to the line 38. Thus we have provided a remote control system for turning current on and off to the motor generator and thence to a series of motors 50, and at the same time for varying the current supplied to the motors at the motors themselves.

If our switch is to be used on a direct current system, the switch may be connected to the power supply lines, as indicated by broken lines in Fig. 1. The direct current power supply lines are indicated by reference numerals 51 and 52. The line 51 runs directly to the work and the line 52 to the switch point 27 and is continued from the switch point 28 to the work by way of line 43. The work in this case might be a rotary

converter. To supply the magnet coil 12 with energy, lines 53 and 54 are tapped off from the lines 51 and 52 and connected respectively to the binding posts 34 and 35, resistances 55 and 56 are introduced in the lines 53 and 54 respectively, to cut down the current supplied to the magnet and the control circuit.

Instead of tapping the main power supply lines, we may connect a battery across the binding posts 34 and 35 to furnish the current necessary for operating the magnet coil 12.

The nature of the work connected to the main circuit and the apparatus connected across lines 38 and resistances 48, may be varied at will. For instance, in place of the motor generator, 44, 45, we may connect the power lines 41 and 43 to a radio receiving set, and the lines 46 and 47 may extend from the set to loud speakers which would take the place of the motors 50. The resistances 48 would then provide for controlling the volume of reception at the loud speakers, and the current to the receiver set could be turned on from points adjacent the loud speakers, or from any other desired points by means of suitably located push buttons 39.

Having thus described our invention and with the understanding that various other changes, alterations and modifications can be made in the construction of our invention and the arrangement of various parts without departing from the spirit and scope of our invention.

We claim:

1. In a switch of the character described, a star wheel, a spring-pressed switch arm engaging the star wheel, the switch arm being formed with a bearing surface and a recess contiguous thereto, said surface and recess being adapted to be engaged successively by a tooth of the star wheel, and means for rotating the star wheel intermittently by steps of half a tooth space, whereby during successive steps of the star wheel the switch arm will be alternately moved in one direction by a tooth engaging said bearing surface and moved in the other direction by spring pressure as the tooth enters the recess.

2. In a switch of the character described, a spring-pressed switch arm, a contact point adapted to be alternately engaged and disengaged by the switch arm, a star wheel against which the switch arm is pressed, the switch arm being formed with a bearing surface and a recess adapted to be engaged successively by a tooth of the star wheel, a ratchet mechanism adapted to turn the star wheel by steps of half a tooth space, and an electro-magnet adapted to operate the ratchet mechanism, whereby at one step of the star wheel the switch arm will be moved

against the spring pressure into engagement with the contact point by a tooth engaging said bearing surface and at the next step will be moved by the spring pressure to disengage the contact point as the tooth clears 70 the bearing surface.

3. In a switch of the character described, a spring-pressed switch arm, a star wheel against which the switch arm is pressed, a lantern gear supporting the star wheel, the lantern gear having twice as many pins as there are teeth in the star wheel, a pawl adapted to successively engage the pins of the lantern gear, an armature carrying the pawl, an electro-magnet adapted to attract 80 the armature, and a spring adapted to return the armature, whereby upon each actuation of the electro-magnet the pawl will turn the star wheel through a half a tooth space, the spring arm being formed with a bearing surface and a recess adapted to alternately engage a tooth of the star wheel, whereby on successive movements of the star wheel the switch arm will be alternately moved in one direction by engagement of a 85 tooth with the bearing surface and in the other direction by spring pressure as the tooth enters the recess.

4. In a switch of the character described, a spring-pressed switch arm, a star wheel 95 against which the switch arm is pressed, a lantern gear supporting the star wheel, the lantern gear having twice as many pins as there are teeth in the star wheel, a pawl adapted to successively engage the pins, an armature carrying the pawl, an electro-magnet adapted to attract the armature, a spring adapted to return the armature, and an adjustable stop to limit movement of the pawl, whereby upon each actuation of the 100 electro-magnet the pawl will turn the star wheel through half a tooth space, the spring arm being formed with a bearing surface and a recess adapted to alternately engage each tooth of the star wheel, whereby on 105 successive actuations of the electro-magnet the switch arm will be alternately moved in one direction by engagement of a tooth with said bearing surface and moved in the other direction by spring pressure as the tooth 110 enters the recess.

5. In a switch of the character described, a spring-pressed switch arm, a star wheel against which the switch arm is pressed, the switch arm being formed with a bearing 120 surface and a recess adapted to be engaged successively by a tooth of the star wheel, a U-shape magnet core, an energizing coil about one leg of the core, an armature hinged to the other leg of the core, a spring holding the armature normally clear of the former leg of the core, a shading coil on the core, a ratchet wheel secured to the star wheel, a ratchet pawl carried by the armature, and a spring serving to hold the pawl

in engagement with the ratchet wheel, whereby at each energizing of the magnet the star wheel will be moved through an angle equal to half the tooth spacing of the star wheel.

5 Signed at New York, in the borough of Manhattan, and in the county and State of New York, this 3rd day of February, 1927.
